UNITED STATES PATENT OFFICE.

ERVIN H. ZIMMERMAN, OF PERRY, ILLINOIS.

ELEVATOR.

1,090,670.

Specification of Letters Patent. Patented Mar. 17, 1914.

Application filed August 29, 1912. Serial No. 717,639.

To all whom it may concern:

Be it known that I, ERVIN H. ZIMMERMAN, a citizen of the United States, and a resident of Perry, in the county of Pike and State of Illinois, have invented certain new and useful Improvements in Elevators, of which the following is a specification.

My invention is an improvement in elevators, and has for its object the provision of an elevator which may be transported from place to place and may be operated from any suitable source of power, and which is especially adapted for handling grain, such as corn and wheat, vegetables, such as potatoes or any other article that may be handled with a scoop shovel.

Referring to the drawings, Figure 1 is a side view of the improved elevator, Figs. 2 and 3 are sections on the lines 2-2 and 3-3 respectively of Fig. 1, Fig. 4 is a vertical longitudinal section of the elevator, Fig. 5 is an enlarged perspective view of a portion of the endless carrier, Fig. 6 is a detail perspective view of the lifting mechanism for the dumping device or movable section of the elevator, and Fig. 7 is a similar view of the connection between the said section and the fixed section.

The present embodiment of the invention is shown supported on a carriage, consisting of a body 1, and front and rear axles 2 and 3, each axle having journaled on the ends thereof a pair of wheels 4. A tongue 5 is connected with the front axle for convenience in transporting the elevator, and a pair of standards 6 is secured to the front end of the body, and at each side thereof. Each standard 6 is braced against the body by front and rear braces 7 and 8, and at the rear of the body a pair of uprights is arranged, each upright consisting of a substantially vertical portion 9 and an inclined portion 10, the said portions 9 and 10 being integral at their upper ends, and each upright has a bearing for receiving a shaft 11 arranged transversely of the body.

A shaft 12 is journaled on the standards 6, at the upper ends thereof, and the main section of the elevator is supported between the standards and the uprights. The said main section consists of spaced side plates, each side plate being composed of a bottom or lower section 13, and a top or upper section 14, the said sections of each side plate being connected together by a hinge 15. The hinge 15 is at the upper edge of the sec-

tions and forms with the sections a species of rule joint which permits the sections to fold upwardly, but which prevents them from folding downwardly. At their upper ends, the sections 14 are connected by a curved plate or hood 16, and a shaft 17 is journaled between the said ends of the side plates adjacent to the hood. A shaft 18 is journaled transversely of the side plates at their lower ends, and stub shafts 19 are journaled below and in front of the shaft 18 on the body 1. Each of the shafts 17, 18 and 19 is provided with sprocket wheels 20, one near each end, and an endless belt or chain 21 is supported on the sprocket wheels of the shafts 17 and 18 adjacent to each side plate. The chains are connected at spaced intervals by vertically arranged slats or buckets 22, and a floor 23 is arranged transversely of the side plates between the upper and lower runs of the chains. The forward end of the said floor is curved around the shaft 17 as shown at 24 in Fig. 4, and the sprocket wheels 20 on the shafts 19 also engage with the endless chains, but with the lower runs thereof, preventing the lower runs from sagging away from the shaft 18.

Pulleys 25 are secured to the shaft 12, and cords or cables 26 pass over the said pulleys. One end of each cord is connected to a bracket 27 on the outer face of the adjacent side plate and the other end of each cord winds upon a drum 28, journaled on the upper edges of the body of the carriage. A handle 30 is provided for the drum and a ratchet wheel 31 is secured to the drum at each end. A pawl 32 cooperates with each ratchet wheel to hold the drum in position, and it will be evident that when the pawl is released, the elevator may be raised or lowered by turning the drum in the proper direction.

The lower end of the main section of the elevator is supported by angle brackets 33, each of which has one portion secured to the bottom of the carriage body by means of bolts 34, and the other portion of each angle bracket is provided with a bearing 35, for receiving the shaft 18.

It will be noted from an inspection of Figs. 1 and 4, that the side plates 13-14 are longitudinally slotted at the lower runs of the belts, as shown at 36, so that the said runs of the belts are visible from the slot. Straps 37 are riveted to the side plates and extend transversely of the slots of each side

plate. The sections of each side plate are held normally in alinement by means of bolts 38, the said bolts passing through registering openings in laterally extending lugs 39, on brackets 40, which are secured to the meeting ends of the sections 13 and 14 of the side plates.

The shaft 17 is journaled in bearing blocks 41, slideable in guides 42, arranged in openings in the sections 14 of the side plates. Each bearing block is slideable in the guide, and threaded rods 43 are rotatably connected with the blocks, each of the said rods being threaded through a lug 44, on the adjacent guide 42. It will be evident that when the rods 43 are turned in the proper direction, the shaft 17 will be moved toward or from the shaft 18.

The shaft 18 is provided with a belt 20 wheel 45 outside of the adjacent side plate and with sprocket wheels 46 and 47, also outside of the side plates. The sprocket wheels 46 and 47 are connected by sprocket chains 48, but one of which is shown, with 25 sprocket wheels 49 on a shaft 50, journaled in the ends of extension plates 51 to be later described.

A sprocket wheel 52 is journaled loosely on the shaft 18 outside of the sprocket wheel 47 and the said wheel 52 is provided on one of its faces with one section of the clutch, the other section 53 of the clutch being feathered on the shaft 18, and moved toward and from the wheel 52, by means of 35 a lever 54 pivoted to a bracket 55 on the adjacent side plate. The said lever 54 is provided with a fork for engaging a groove 56 on the clutch section 53, and the lever is held in adjusted position by means of the 40 usual latch mechanism and toothed quadrant 57.

Each of the extension plates 51 before mentioned, is pivoted at its inner end on the adjacent end of the adjacent plate 13, 45 each plate 51 having a laterally extending pin 58 for this purpose. The extension plates and connected parts form an auxiliary or loading section of the elevator. The pin 58 is held in U shaped bearing blocks 59, each of which is secured to the adjacent side plate 13 and the shaft is held in the bracket by means of cotter pins 60, passing through the arms of the brackets.

The shaft 50, before mentioned, is journaled at the other end of the extension plate 51 and the endless belts or chains 21 pass over sprocket wheels 61 on the said shaft 50. The endless carrier formed by the chains 21 and the slats 22 thus extends from the shaft 17 to the shaft 50, and the sprocket wheels of the shafts 18 and 19 support the upper and lower runs of the said chains at the junction of the adjacent ends of the main and the auxiliary or loading sections 65 of the elevator.

The lower edge of each extension plate 51 is rounded as shown at 62, and a bar 63 is arranged below said edge in spaced relation and is held in place by means of straps 64, which are riveted to the extension plates 70 and to the bar.

Each of the stub shafts 19, before mentioned, is journaled on a bracket 69, secured to the adjacent side plate 13, the sprocket wheel 20 being on the inner side of the 75 bracket.

A bracket 70 is secured to each of the extension plates 61 on the outer face thereof, and the upper end of each bracket is off-set laterally from the extension plates, and is provided with a journal pin 71, at its upper end. A lever 72 is pivoted to each journal pin at one of the ends of the lever, and the said lever is held in place on the pin by a cotter pin 73. The free end of each lever 85 is curved upwardly as shown at 74 and is provided with a lateral outwardly extending lug 75.

The shaft 11, before mentioned, is square in cross section, and an arm 76 is held on the shaft outside of each upright, and each arm is provided with a square opening for receiving the shaft. The outer end of each of the said arms is curved downwardly as shown at 77, and is pivoted to the adjacent lever 72 as indicated at 78, at the junction of the straight and the curved portions of the said lever. A crank 79 is arranged on the shaft at one end and it will be evident that when the shaft 11 is oscillated by means of the crank, the auxiliary or loading section of the elevator will be swung upwardly and forwardly. The upper run of the endless carrier travels toward the hood 16, and anything dumped upon the said carrier at 105 the auxiliary section of the elevator will be carried toward the hood and will be delivered at the upper end thereof. The said upper end may be raised or lowered in accordance with the height of the place to 110 which the material is to be delivered, and a deflecting board 80 is arranged at the upper end of the main section of the elevator for preventing the material from falling rearwardly. The loading section of the elevator may be turned up in dumping position during transportation. The loading section may be also released from the main section by removing the cotter pins 60.

A belt 81 from a suitable source of power, 120 is connected to the band wheel 45, for operating the elevator.

The slats 22 (Fig. 5) are provided with laterally extending pins 82 rectangular in cross section and the said pins are received in similarly shaped openings in the links 21 of the chains. Each slat is also provided with an outwardly extending lug 83, at each end of its upper edge, the said lug extending over the chains.

When not in use, the main section of the elevator may be lowered on to the body of the carriage and the upper portion of the main section may be folded back upon the lower portion by releasing the bolts 38.

The tension of the endless carrier may be varied by means of the bolts 43.

In operation, the endless carrier is started, by connecting the clutch sections 52 and 53.

10 The material to be lifted may be dumped on the loading section of the carrier by means of the dump cart 84, shown in Fig. 1, or in any other suitable manner, and is carried by the endless carrier and delivered at any desired height, as for instance into a crib, bin or loft. The arms 76 and the lever 72 lock the movable section of the elevator in either lowered or raised position.

15 The device may be of any suitable or desired size and dimension.

I claim:

1. In combination, a fixed support, and a dumping frame pivoted to the support, and means for swinging the dumping frame into an approximately vertical position, said means comprising an upright at each side of the support, a shaft journaled in the uprights transversely of the dumping frame, arms on the shaft, a lever pivoted to each side of the dumping frame, each lever and each arm being curved at its outer end, a pivotal connection between the outer end of each arm and the adjacent lever near the

junction of the curved and straight portions of the lever, the free end of each lever having a lateral lug overlying the upper edge of the adjacent arm, and means for oscillating the shaft.

2. In combination, a fixed support, and a dumping frame pivoted to the support, and means for swinging the dumping frame into an approximately vertical position, said means comprising a shaft on the support above the adjacent end of the dumping frame, a lever pivoted to each side of the dumping frame, and arms rigid with the shaft at one end and pivoted to the adjacent lever at the other, and means for oscillating the shaft.

3. In a device of the character specified, a dumping frame, and a support, and means on the support for swinging the dumping frame, said means comprising a shaft provided with radial arms, levers pivoted to the dumping frame at one end and to the free ends of the arms at the other, each lever being extended beyond its pivotal connection with the arm, and having means for engaging above the arm to limit the downward movement of the arms and levers, and means for oscillating the shaft.

ERVIN H. ZIMMERMAN.
